UNITED STATES PATENT OFFICE

WILLIAM D. WILCOX, OF IDAHO FALLS, IDAHO

COMBINATION GAS RANGE AND WATER HEATER

Application filed July 17, 1928. Serial No. 293,344.

My invention has for its purpose the utilization of the heat carried away from the top and oven burners of a gas range in the combustion products for the purpose of heating water. The manner in which this utilization is accomplished will be better understood by reference to the accompanying drawings: Figure 1 shows a front view. Figure 2 shows 5 the range as viewed from above with a cross section across the water heater above the level of a gas burner. Figure 3 shows a vertical cross section on line 3-3 of Figure 1. A is an oven, heated by gas burners 1 and 2. B is a cooking top containing gas burners 10 5, 6 and 7. C is a secondary heating chamber containing water coils 11. The products of combustion from burners 1 and 2 pass from the interior of A through 3 into C. A damper 4 is provided to close 3 if desired. B is 15 closed except at the front and rear which is open to C unless closed off by damper 8. 10 is a passage from the cooking top B into C. 9 is a gas burner extending under the heating coils in C. 12 is a flue outlet from C. 20

25 The mode of operation is very readily understood. When cooking is in progress the combustion of the gas in burners 5, 6 and 7 is supported by air entering the front by reason of the draft created by flue 12. Damper 8 will be open, damper 4 closed unless it is desired to bake at the same time. The combustion products pass up through 10 and C and escape through flue 12, imparting a portion 30 of their heat to the water in pipes 11. Where hot water is desired at a time when cooking or baking is not in progress, it may be obtained by lighting burner 9, air being supplied by keeping open dampers 4 and 8. I do not 35 restrict myself to the particular design of parts shown in the drawings.

What I claim as new and desire to protect by the issuance to me of Letters Patent is:

1. In a combined gas range and water heater, the improvement which comprises in combination an enclosed cooking top, a

chamber adjacent thereto enclosing water containers, gas burners in the cooking top, means for admitting air to the interior of the cooking top, a passage connecting it with the chamber enclosing water containers, 55 means for closing this passage, means for withdrawing combustion gases from the upper part of the chamber enclosing water containers.

2. In a combined gas range and water heater, the improvement which comprises in combination, an enclosed cooking top, an oven below the cooking top, a chamber enclosing water containers, a passage from the cooking top to this chamber, means for closing this 60 passage, a passage from the oven to this chamber, means for closing this passage, gas burners in the cooking top and burners underneath the oven, means for admitting air to these burners, means for withdrawing combustion products from the upper portion of the chamber enclosing water containers. 70

3. In a combination gas range and water heater, the improvement which comprises in combination an enclosed cooking top, a chamber enclosing water containers, burners in the cooking top, means for admitting air to these burners, a passage connecting the interior of the cooking top with the chamber enclosing water containers, means for closing 75 this passage, oven-burners underneath the oven, means for admitting air to the burners, a passage from the upper part of the oven connecting it with the chamber enclosing water containers, means for closing this 80 passage, a burner below the water containers, means for admitting air thereto, means for withdrawing combustion gases from the upper part of the chamber enclosing water containers. 85

In witness whereof, I have affixed my signature.

WILLIAM D. WILCOX.
